HARRIE A. BALLARD, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

LOOPER MECHANISM FOR SEWING-MACHINES.

1,075,082.

Specification of Letters Patent.

Patented Oct. 7, 1913.

Application filed December 26, 1907. Serial No. 408,034.

To all whom it may concern:

Be it known that I, HARRIE A. BALLARD, a citizen of the United States, of Boston, in the county of Suffolk and State of Massachusetts, have invented certain new and useful Improvements in Looper Mechanism for Sewing-Machines, of which the following is a specification.

This invention has relation to looper mechanisms for shoe-sewing machines, and it is applicable to both chain-stitch and lock-stitch machines.

The object of the invention is to provide a simple mechanism by which the looper may be given the desired movement so that its nose may be caused to lay the thread as may be desired about the needle.

Referring to the accompanying drawings, Figure 1 represents a portion of a chain-stitch shoe-sewing machine, and illustrates in addition to the looper mechanism, the needle and its actuating mechanism and the thread finger and its actuating mechanism.

Fig. 2 represents in plan view the yoke or support for the looper and the looper bar. Fig. 3 is a detail view showing the eccentric sleeve or bushing for varying the orbit of movement of the looper and for varying the position of the looper nose relatively to the needle. Fig. 4 represents an embodiment of the invention which is particularly adapted to lock-stitch machines such as are employed for stitching the sole to the shoe.

Referring to the drawings and particularly to Figs. 1, 2 and 3, the needle *a* is supported by a carrier *b* which is journaled on a stud *c*. The needle carrier is actuated by a toothed segmental lever *d*, the teeth of which engage segmental teeth on the needle carrier. The lever *d* is oscillated about the pivot *d'* by an eccentric *d''* on the main shaft *c*. This mechanism is fully described in my co-pending application Serial No. 407,143 filed December 19, 1907, to which reference may be had for a complete machine embodying the present invention. *f* indicates a thread finger which may be oscillated about a stud *f'*. Said thread finger is attached to an arm *f''* having on its end segmental gear teeth engaging the complementary teeth on

the end of a lever *f'''* pivoted on the stud *d'*, and having one arm engaged with the cam groove of a suitable cam not shown, on the power shaft *e*. The looper is indicated at 10. Its nose 11 is arranged with reference to the needle so that it may be moved in an orbit about the same to lay the thread upon the needle and to cross the bights of the loop, as explained in my co-pending application Serial No. 242,489, filed January 24, 1905. The upper end of the looper is clamped in the bent end of what I may call the looper bar, as shown in Fig. 2. This bar is reciprocated and is also swung around an axis or center so that its end is caused to move in an endless path. The bar is mounted to slide in guides 13 in the ends of a yoke or support 14. The said yoke is provided midway between its ends with a depending stud 15 which is journaled in an eccentric 70 sleeve or bushing 16. This sleeve or bushing is secured in a suitable bracket 17 and is provided with a milled or angular head 18 by which it may be rotatively adjusted. After adjustment, the eccentric sleeve is 75 held in place by a set screw 19. The rear end of the looper bar is pivoted upon a crank pin 20 which projects from a disk 21 formed on or secured to a shaft 22. The rotation of this shaft effects the reciprocation 80 of the looper bar and the oscillation of the looper bar and the yoke or support 14 about the axis of the stud 15 as will be readily understood. On the other end of the shaft 22 is secured a spiral gear 23 which intermeshes with, and is driven by, a complementary gear 24 on the driving shaft *e*.

In a chain-stitch machine, such as utilized for attaching a welt to the upper and inner sole of a shoe, it is desirable to lay 90 the thread upon the needle with the bights crossed so that the loop will form a black-wall hitch when the needle is withdrawn. The teeth of the gear 23 and the teeth of the gear 24 may be so formed that, during 95 one rotation of the power shaft *e*, the shaft 22 may be rotated first in one direction through an arc of approximately 450° and then through an arc of 90° in the opposite direction. In order to cause a dwell of the 100

looper in its different positions, and after the movements described, the gear 24 may be formed with peripheral ribs to engage complementary grooves in the gear 23, as described in my said co-pending application Serial No. 407,143 filed December 19, 1907.

By rotatively adjusting the eccentric sleeve or bushing 16, from the position shown in Fig. 2 through an arc of 90° to the right 10 or to the left, the looper will be caused to move through an arc of a greater or a smaller radius as the case may be. But, should the bushing be moved through an arc of approximately 180° from the position 15 shown in Fig. 2, the yoke or support will be bodily adjusted transversely of the looper bar so as to adjust the looper relatively to the needle.

In Fig. 4, I have shown the looper mechanism which is applicable to lock-stitch machines, such as illustrated in my co-pending application Serial No. 331,529, filed August 21, 1906. There is practically no difference 20 between this looper mechanism and that just described, except that the looper 25 projects upwardly instead of downwardly. It is shown as clamped in the end of a cylindrical looper bar 26 adapted to slide in guides 27 in the yoke 28 which is pivoted upon an eccentric portion of rotatively adjustable stud 29. The rear end of the looper bar is secured in a socket 30 which is pivotally connected to a crank pin 31 projecting from a disk 32 on the shaft 33. On the 30 upper end of the shaft is a spiral gear 34 intermeshing with, and driven by, a complementary gear 35. In this case it need not be necessary to cross the bights of the loop on the needle, and consequently, the gears 40 are so formed that the looper is caused to move first through an arc of approximately 240° where it dwells and then through an arc of 120° to its original starting point.

Having thus explained the nature of my 45 said invention and described a way of constructing and using the same, although without attempting to set forth all of the forms in which it may be made or all of the modes of its use, I declare that what I claim is:—

50 1. In a sewing machine, a curved needle and a looper mechanism comprising a looper, a sliding looper bar from which said looper projects laterally, a support in which said bar is mounted to slide and having a pivot 55 between its ends, and means rotatable about an axis substantially parallel to said pivot and connected to the end of said bar for reciprocating it and rocking said support about its pivot to cause the looper to encircle the needle.

2. In a sewing machine, a curved needle, a looper mechanism comprising a looper, a sliding looper bar, a support pivoted between its ends and having separated guides

for said bar, and a crank rotatable about an 65 axis transverse to said bar and connected to the end of said bar for rocking said support about its pivot and sliding said bar relatively thereto to cause the looper to encircle the needle so as to lay the loop thereon. 70

3. In a sewing machine, a curved needle and a looper mechanism comprising a pivoted yoke having guides at its ends, a looper bar mounted to slide in said guides on said yoke, a looper attached to one end of said 75 bar and projecting laterally therefrom, and a crank shaft whose axis is transverse to said looper bar and having a crank connected to the other end of said bar to reciprocate said bar relatively to said yoke and 80 rock said yoke about its axis to cause the looper to encircle the needle.

4. In a shoe sewing machine, a barbed needle, looper mechanism comprising an oscillatory support, a looper bar mounted 85 upon said support in bearings in which it is movable longitudinally of its own length, the axis of said bar being transverse to the axis about which said support is movable, a looper carried by said bar for laying the 90 needle thread in the needle barb, an actuator for said bar, and means for causing said actuator to describe an endless path about an axis substantially parallel to the axis about which said support is movable, 95 said actuator and bar having contiguous faces whereby the bar is reciprocated longitudinally and laterally to cause the looper to encircle the needle.

5. In a sewing machine, a curved needle, 100 a looper mechanism comprising a looper, a looper bar, a support for slidably supporting said looper bar, a pivot for said support, a crank arranged transversely to and connected to said looper bar for sliding it 105 and rocking said support, and an eccentric sleeve for said pivot, whereby said looper may be adjusted with respect to said needle substantially as set forth.

6. In a shoe sewing machine, a barbed 110 needle, looper mechanism comprising a looper for laying the needle thread in the needle bar, a bar for carrying said looper, a movable support for said bar, a stationary support for said movable support, and 115 movable support being movable by said bar, and said bar being movable relatively to said movable support whereby it is capable of compound movement, an actuator for said bar, and means for causing said actuator to 120 describe an endless path, said bar and said actuator having contiguous faces whereby said bar is given a compound movement to cause said looper to encircle the needle.

7. In a sewing machine, a curved needle, 125 a main driving shaft, a looper bar extending from the rear toward the front, a looper projecting laterally from said bar, an up-

right shaft geared to said driving shaft and having a crank connection with said looper bar, and an oscillatory support for said looper bar in which said bar may slide, said 5 parts being constructed and arranged whereby said looper may be caused to encircle the needle to lay the loop thereon.

In testimony whereof I have affixed my signature, in presence of two witnesses.

HARRIE A. BALLARD.
